AUTO MONOPLANE

Edward F. Wagner, Philadelphia, Pa.

Application December 16, 1935, Serial No. 54,538

4 Claims. (Cl. 244—48)

My invention relates to new and useful improvements in an auto monoplane and has for one of its objects to provide an aeroplane with wings that can be folded into parallelism with the fuselage so the machine can be used as an automobile.

Another object of the invention is to construct a unique mechanism for permitting the wings to be moved into folded or open positions.

10 Another object of the invention is to provide a novel locking mechanism for temporarily fixing the wings in either an open or folded position.

Another object of the invention is to generally improve aeroplanes of this type and particularly 15 to provide means for pivotally mounting the wings on a common center, the structure of which I choose to term a fifth-wheel.

Another object of the invention is to provide 20 wing supporting arms having bifurcated branches for attachment to the wing spars and journals for pivotal connection to a centrally located mast.

25 A further object of this invention is to provide an arrangement of propellers that assist in lifting the aeroplane and therefore also function as safety devices during forced or other landings.

A still further object of the present invention 30 is to provide auxiliary motive means for the lifting propellers whereby they may be operated independently of the driving propeller which latter includes either tractor or pusher screws.

With the above other objects in view, this invention consists of the details of construction and combination of elements hereinafter set 35 forth and then designated by the claims.

In order that those skilled in the art to which this invention appertains may understand how to make and use the same, I will describe its construction in detail, referring by numerals to 40 the accompanying drawings, in which:

Fig. 1 is a side elevation of an auto-monoplane constructed in accordance with my invention.

Fig. 2 is a top plan view thereof showing the wings in open position and illustrating in dotted lines the closed or folded position thereof, a portion of one wing being broken away.

Fig. 3 is a front elevation of the aeroplane.

Fig. 4 is a view looking at one side with portions of the fuselage broken away and shown in 50 section to illustrate the interior arrangements and locations of some of the parts.

Fig. 5 is a plan view of the wing assembly with the two wings folded or closed.

Fig. 6 is an enlarged end view thereof.

55 Fig. 7 is a fragmentary view similar to Fig. 6

showing a portion of the locking mechanism in a position to permit a wing to be swung from one position to another.

Fig. 8 is an enlarged section of one wing on the line 8—8 of Fig. 5.

Fig. 9 is a cross section of the lock keeper, on a reduced scale, showing the positions of the keeper notches and slots.

Fig. 10 is a diagrammatic view of the several driving mechanisms and controls, and 10

Fig. 11 is a fragmentary vertical section of Fig. 6.

In carrying out my invention as herein embodied 15 represents the fuselage of the aeroplane of suitable size, shape and design with 15 the main power plant 16 located in the cowl 17 having any number of suitable louvers 18. This main power plant 16 operates the driving propeller 19 and the rear or propulsion wheels 20 independently of each other. To this end I have 20 shown, particularly in Fig. 10, means 21, such as a chain, for driving the counter shaft 22 from the engine shaft 23 and on said counter shaft 22 is fixed an internally tapered fly wheel 24, or its equivalent, with which the clutch cone 25 co- 25 operates to transmit motion from the counter shaft 22 to the clutch shaft 26 on which said cone is splined so as to revolve therewith and slide thereon. The clutch cone is moved longitudinally of its shaft by a clutch pedal 27 or similar 30 means.

The clutch shaft 26 is connected with the transmission 28 comprising the usual gears employed in automobile construction and mounted in a gear box 29. The speed change gears of 35 the transmission are actuated by the gear shifting lever 30 and motion is transmitted to the drive shaft 31, which is connected to the transmission by the universal joint 32, and thence through the differential 33 to the rear axle for 40 the rear wheels 20.

In order to stop the machine brakes 34 are provided which, for purposes of illustration, are shown as associated with the rear wheels and having brake rods 35 connected to a brake pedal 45 36.

In addition to the rear wheels, the aeroplane is mounted upon front wheels 37 which are also used as landing wheels and when the machine is being used upon a roadway said front wheels 50 are guided by a steering gear including the steering post 38 and the steering wheel 39. This steering wheel as well as the gear shifting lever, brake and clutch pedals are located in easy access of the operator who may be seated on a seat 55

40 in the cockpit. The front wheel structure is provided with extra heavy duty shock absorbers 41 and suitable struts 42.

5 A control stick 43 and a rudder bar 44 are also located adjacent the operator's seat 40 for actuating the elevators 45 and the rudder 46 respectively through suitable connecting means 47. The elevators are connected to the horizontal stabilizers 48 and the rudder is hinged to the vertical 10 stabilizer 49.

15 Under the fuselage at the tail end is a safety skid 50 to prevent the elevators or other parts contacting with the ground at the time of landing should the operator give too much "lift" to the forward end.

20 The interior of the aeroplane may be divided off in any desirable number of compartments for passengers, goods being shipped, storage of gasoline, oil or other supplies and in carrying out this 25 feature of invention, I have shown an additional seat 51 in the cockpit and this seat as well as the operator's seat 40 may be adjustably mounted on tracks 52.

30 The wings 53 have the usual ribs 54 and spars 55 and to the latter are fastened the branches 56 of the bifurcated ends of the supporting arms 57, the opposite ends of which have journals 58 for registration with the hollow mast 59 mounted in the fuselage and projecting a considerable distance above the top thereof. This mast is fixed at its lower end in a bracket 60 and is further supported in the upper part of the fuselage frame and the roof of a canopy 61 located above the cockpit.

35 On top of the canopy roof is mounted a lock keeper 62 in the form of an inverted cup with a flange 63 surrounding its lower open end to receive the attaching means 64, such as bolts, and the top wall has a hole through which the mast projects while the side walls have two slots 65 formed therein which slots terminate at both ends in notches or depressions 66. A locking member or catch 67 is connected at one end to each wing supporting arm by a bolt 68 on which the catch 40 is slidably mounted and such catch is normally urged away from its respective supporting arm by a spring 69 which may be of the coiled type and positioned about the bolt 68.

45 The other end of the catch projects into the keeper for registration with either of the notches and the slot and said other end of the catch is urged into a notch by a spring 70 located between a vertically fixed element, such as the wing supporting arm or a collar 71, and the catch 67. A 50 hand screw 72 projects through the catch and is threaded into the wing supporting arm for withdrawing the catch from a notch, as in Fig. 7, by compressing the springs 70 and 69.

55 With the catch withdrawn from a notch, the wing may be readily rotated from one position to another and when the desired position is reached the hand screw is backed off sufficiently to allow the catch 67 to enter the aligned notch and the wing will be securely held in place.

60 The journals 58 of the wing supporting arms 57 are positioned above the keeper 62 and may have one or more washers 73 located between them and above the uppermost journal is a washer 74 against which a spring 75 bears to resiliently hold 65 the wing supporting arms against undue vertical movement, said spring also bearing against a nut 76 adjustably connected to the mast for varying the tension of said spring.

70 The wings are supported in their open positions 75 by struts 77 pivoted at their lower ends by thumb

screws 78 to the outside of the fuselage and detachably connected at their upper ends to the underside of the wings by bolts 79 or equivalent fastening means. When the wings are to be folded back or closed the struts 77 are disconnected 5 from the wings and swung down into hooks 80 on the sides of the fuselage as shown in dotted lines in Fig. 1. The wings are further supported in both of their positions by hangers 81 having their ends fastened to the mast and the tops of the 10 wings and said hangers are adjustable through the medium of turnbuckles 82.

15 When the wings are in a folded or closed position they are supported intermediate their ends by an open-work platform 83 mounted on top of the fuselage and the leaves 84 hinged at 85 to the sides of said platform and adjustable to different heights by props 86, one hinged at 87 to each leaf 84 and having hand screws 88 for threaded connection with the plates 89 on the 20 sides of the fuselage and provided with a vertical row of spaced holes 90 to receive the screws.

25 After the wings have been closed or folded so they rest on the platform 83 the leaves 84 are raised to move them into engagement with the undersides of the wings which do not rest directly upon the platform.

30 A shaft 91 is mounted in the hollow mast with its ends projecting beyond the ends of the said mast and the lower end of said shaft extends outside of the fuselage where it is further supported by a bracket 92. On the upper end of the shaft 91 is fixed a lifting propeller 93 of the tractor type and on the lower end of said shaft is fixed another lifting propeller 94 of the pusher type. 35

35 Still another lifting propeller 95 of the tractor type is located above the fuselage at the after part of the machine and is fixed to a vertical shaft 96 passing through the top of the fuselage in a bearing 97 and a bracket 98. The lifting 40 propellers are all driven by an auxiliary motive means 99, Fig. 4, which may be any suitable prime mover but for purposes of illustration it is shown as an internal combustion motor geared to the shaft 96 and motion is transmitted from said 45 shaft to the shaft 91 as by a chain 100 passing around sprockets on both of said shafts although other equivalent means can be utilized. Access to the auxiliary motive means and other parts in the after end of the machine may be had 50 through one or more doorways normally closed by a door or doors 101, one of which is shown in Fig. 1.

55 Whenever a landing is desirable or necessary, the lifting propellers can be operated in conjunction with or independently of the driving propeller and will cause the machine to land practically in a vertical direction and when taking off said lifting propellers may be used to raise the machine perpendicularly. 60

60 Two instrument boards or panels 102 and 103, Fig. 4, are provided and preferably they are located one above the other in the cockpit. One of them carries the aeroplane instruments and the other the automobile instruments. 65

65 The machine is equipped with head lamps 104, a front license bracket 105, a rear lamp 106 and a rear license bracket 107 for use when the machine is being run as an automobile and additional lamps 108 are provided for navigation purposes when the machine is used as an aeroplane 70 and the latter lamps are shown as suspended from the wings.

70 When the wings are in their open, outstretched positions they may be further supported by a 75

cross-bar 111 having each end detachably connected to a separate wing of the machine by thumb or wing bolts 112.

I have not particularly pointed out or described 5 the ordinary or well known elements of the aeroplane but all of the necessary parts are provided such, for example, as the ailerons 109 on the wings and a trimmer 110 on the rudder.

Of course I do not wish to be limited to the 10 exact details of construction herein shown and described as these may be varied within the limits of the appended claims without departing from the spirit or scope of my invention.

Having thus fully described my invention what 15 I claim as new and useful is:—

1. An aeroplane comprising a fuselage, a canopy over the cockpit thereof, a mast mounted in said fuselage and projecting through and above the canopy, wings, supporting arms having 20 their outer ends attached to the spars of the wings and their inner ends journaled on the mast so they may be moved into open outstretched or closed positions, a lock keeper mounted on top of the canopy and under the 25 wing supporting arms, said keeper having slots in its side walls, each slot having a notch at both ends, a catch carried by each supporting arm and having an end projecting into the keeper for registration with a slot and the notches thereof, springs urging the catches away from the supporting arms whereby they may be caused to enter the notches, and means to move the catches out of the notches to permit said catches to travel through the slots.

35 2. The structure in claim 1 in combination with a platform mounted on top of the fuselage to

support the wings when folded, leaves hinged to the sides of said platform whereby they may be projected into engagement with the wings while the latter are in folded positions, and props for supporting said leaves in various selected elevations. 5

3. In combination, a wheel supported fuselage having a cockpit, a canopy over said cockpit, a mast in said cockpit and protruding above the canopy, wings journaled on the mast whereby 10 they may be selectively moved into open or closed positions, stationary means on the after part of the fuselage on which portions of the wings rest when in closed positions, and means adjustably connected with the first mentioned means to be 15 moved into engagement with the undersides of the wings while said wings are in their closed positions for assisting to support said wings.

4. An aeroplane comprising a fuselage, a mast mounted in said fuselage and projecting above 20 the same, a lock keeper comprised of an inverted cup encircling the mast just above the fuselage, said lock keeper having oppositely positioned circular slots with notches at both ends, means to support said lock keeper, wing supporting arms 25 having their inner ends journaled on the mast one above the other and both above the lock keeper, means to urge said arms toward the lock keeper, spring actuated catches carried by the wing supporting arms and projecting into the 30 lock keeper slots for registration with the notches, means projecting through the catches and threaded into the arms for withdrawing said catches from the notches, and wings carried by said arms. 35

EDWARD F. WAGNER.
